UNITED STATES PATENT OFFICE

101,987

DESIGN FOR LACE

Laurence E. Hart and Herbert E. Lewy,
New York, N. Y.

Application October 24, 1936, Serial No. 65,472

Term of patent 3½ years

To all whom it may concern:

Be it known that we, Laurence E. Hart and Herbert E. Lewy, citizens of the United States of America, residing in Manhattan, county of New York and State of New York, have invented a new, original, and ornamental Design for Lace, of which the following is a specification, reference being had to the accompanying drawing, forming part thereof, wherein,

The figure is a plan view of a piece of lace showing our new design.

We claim:

The ornamental design for lace, substantially as shown.

HERBERT E. LEWY.
LAURENCE E. HART.
